[57] CLAIM

The ornamental design for a headboard for a bed, as shown and described.

DESCRIPTION

FIG. 1 is a front perspective view of a headboard for a bed, showing my design in a closed position;

FIG. 2 is a sectional view through the headboard in open position; and,

FIG. 3 is a front perspective view of the headboard in open position.

The end of the headboard not shown is a mirror image of the end shown while the undisclosed rear surface is flat and unadorned.

The broken-lines depicting a portion of a bed frame in FIG. 1 have been shown for illustrative purposes only.

FIG. 3

FIG. 2

FIG. 1
